UNITED STATES PATENT OFFICE.

WILLIAM M. HOFFMAN, OF BUFFALO, NEW YORK, ASSIGNOR TO SCHOELL-KOPF & CO., OF SAME PLACE.

PUTTING-OUT MACHINE.

SPECIFICATION forming part of Letters Patent No. 288,941, dated November 20, 1883.

Application filed September 7, 1883. (No model.)

To all whom it may concern:

Be it known that I, WILLIAM M. HOFFMAN, a citizen of the United States, residing in Buffalo, in the county of Erie and State of New York, have invented certain new and useful Improvements in Putting-Out Machines, of which the following is a specification.

The object of this invention is to provide a convenient and effective means for putting out the grain, and removing the water or other imperfections from calf, sheep, goat, or other skins.

It will be known that a skin, after being taken out of the tanning-vat, or previous to being hung up to dry, is put through another process, technically termed "putting out." By this means the small pieces of flesh or other imperfections that adhere to the flesh side of the skin are scraped off, and the grain side of the skin is rendered smooth and its appearance otherwise improved, all of which will be fully and clearly hereinafter shown by reference to the accompanying drawings, in which—

Figure 1 is a back view of the machine; Fig. 2, a side elevation, showing a portion of one of the pulleys broken away, so as to expose the pinion and spur-wheel on the other side of it. Fig. 3 is a cross-section through the machine, and Fig. 4 is a front elevation of the machine complete.

The frame *a* of the machine is preferably constructed of wood.

a' is the putting-out cylinder. It is provided with the spiral blades *a''*. The cylinder *a'* is usually made of wood, and the spiral blades are of thin strips of brass rigidly secured thereto. They are arranged, as shown, so as to meet near the center of the cylinder, so that the spirals on each side run in opposite directions. The object of this is to cause the skins to be stretched each way during the operation of the machine. This cylinder is provided with journals *a³* *a⁴*, arranged in boxes made in any well-known way. The driving-pulley *a⁵* (see Fig. 1) is connected directly to the journal or shaft *a⁴*, and consequently with the cylinder.

a⁶ represents a small pulley rigidly secured to the journal or shaft *a³*. This pulley is connected by a belt, *b*, to a larger pulley, *b'*. On

the shaft of the pulley *b'* is secured a smaller pulley, *b²*. From this pulley a belt, *b³*, passes to the pulley *b⁴*. On the inside of the pulley *b⁴* is a pinion, *b⁵*, which gears into a spur-wheel, *b⁶*. This spur-wheel is connected to the shaft 55 *c* of the wooden roller *c'*. (See Fig. 3.)

The object of the belts just described is to give a much slower motion to the roller *c'* than the motion of the cylinder *a'*, the motion of the cylinder being about three hundred and 60 fifty revolutions, and the motion of the roller *c'* about twenty-five. On the inside of the frame is a pinion, *c²*, either near one or both sides of the frame. It is connected to the shaft of the roller *c'* and turns with it. 65

c³ represents a roller made of some yielding material—india-rubber, for instance. This roller is mounted in boxes in the slotted arms *c⁴*. These arms are connected to the arms *c⁵* by means of a bolt and nut, the bolt passing 70 through the slots *c⁶* into the arms *c⁵*, so that the roller may be thereby rigidly secured to the said arms and be capable of an adjustment to or from them. The arms *c⁵* are rigidly fastened to the shaft *d*, which shaft is mounted in 75 boxes *d'*. The boxes *d'* are set in place (see Figs. 2 and 3) so as to be capable of a movement up or down, and are kept down by a spiral or other spring, *d²*. The roller *c'* is made of a hard wood, and is secured in boxes in the 80 frame. (See Figs. 2 and 3.)

d represents a slotted arm secured to the arm *c⁵* by means of a bolt, *d⁴*, which passes through the slot *d⁵*. It will be seen that this arm is made adjustable. Its object is to secure 85 the adjustment of the roller *c'* to or from the putting-out cylinder, after which it is rigidly secured in place by the bolt *d⁴*. There are two arms *c⁵*—one at each side of the machine. At the outer ends of the arms is jointed by a 90 pin, *e*, in the usual way, a connecting-rod, *e'*—one on each arm. The opposite ends of these connecting-rods are secured in a similar way by pins *e²* to the arms *e³* of the foot-step *e⁴*. The arms *e³* are connected to a shaft, *e⁵*. A counter-weight, *f*, on the shaft *e⁵* causes the foot-step 95 to rise after the pressure of the foot is taken off of it.

In operating the machine the skin is thrown over the roller *c'* and the roller started slightly 100

by hand, until it is far enough in to be caught between the rollers c^3 and c^4 . A pressure on the foot-step then brings the two rollers together, and still greater pressure brings the 5 roller c^3 and the skin against the cylinder by lifting the box d' up against the spring d^2 , which cylinder is revolving rapidly and cleans off the small pieces of flesh or other matter adhering to the skin. It also takes out the 10 wrinkles or other imperfections and stretches the skin both ways, as above mentioned, so as to leave it smooth and clear. This operation finishes one-half of the skin. It is then taken out and the opposite end treated in the same 15 way, thereby completing it. By this arrangement the skin is first gripped firmly between the rollers c^3 c^4 , which hold it and cause it to move with the required speed. By increasing the pressure slightly on the foot-step the roller 20 c^3 is brought toward the putting-out cylinder and the skin is brought in contact with it, and is slowly carried past it, moving in a direction contrary to the movement of the putting-out cylinder. One advantage in thus being able 25 to first bring the rollers c^3 c^4 together is that it enables the operator to wring out the water from the skin, if at any time necessary, before bringing the skin in contact with the putting-out cylinder, which is often necessary on account of holes in the skin. It will also be 30

noticed that as the rollers c^3 c^4 are brought together the gear-wheels c^2 g are brought into gear, and as the roller c^4 is continually turning it thereby imparts its movement to the roller c^3 until released from it. The skin being put over the roller c^3 is always in sight, and thereby enables the operator to let off the pressure of the skin from the putting-out cylinder when coming to a hole or a spot on the skin that may be tearing.

35

40

I claim as my invention—

1. In a putting-out machine, a putting-out cylinder and its operating mechanism, substantially as described, in combination with the rollers c^3 c^4 , arms c^5 , mounted in a spring- 45 box, and having the roller c^3 , adjustably connected thereto, and a suitable foot-step for operating the arms, substantially as specified.

2. The rollers c^3 c^4 , the roller c^3 being connected to the arm c^5 , in combination with the spring-box d' , and foot-step and its operating connections for the purpose of holding the skin between the rollers c^3 c^4 , or holding it between them and forcing it against the putting-out cylinder or releasing it, substantially as described.
